John B. Brady ATTORNEY.

UNITED STATES PATENT OFFICE.

OSBORNE I. PRICE, OF FREDERICK, MARYLAND.

RADIO APPARATUS.

Application filed May 31, 1922. Serial No. 564,734.

To all whom it may concern:

Be it known that I, OSBORNE INGLE PRICE, a citizen of the United States, residing at Frederick, in the county of Frederick and State of Maryland, have invented a certain new and useful Improvement in a Radio Apparatus, of which the following is a specification.

This invention relates to rotary condensers and more particularly to that type of variable condenser in which a movable set of plates is adapted to be adjustably interleaved with a stationary set of plates in order to suitably vary the capacity of the condenser.

The particular adaptation selected for the purpose of illustration of my invention is its use in radio receiving sets, wherein a plurality of condensers are customarily employed, some for tuning the receiving circuit to resonance with the incoming signals and others for accumulating and storing impulses of energy for discharge into a signal indicating device.

The object of the invention is the production of a radio receiving set comprising a supporting panel of insulating material, upon which is mounted condensers and other elements in a manner to avoid the use of insulating bushings for the projecting controls, to reduce the number of parts of the several elements and to supply an ease of adjustment of the parts.

A further object of the invention is the improvement of the details of construction of a rotary condenser, and the selection of materials for the parts thereof with a view to avoiding the danger of short-circuiting and the necessity for insulated bearings.

A further object of the invention is the reduction of the number of parts in rotary condensers with the accomplishment of an enlarged ease of movement of the rotating elements and the production of an increased compactness.

Other objects of the invention will herein-after appear in the following description, and the novel features thereof will be particularly pointed out in the appended claims.

In the drawings, in which like reference numerals indicate like parts throughout the

several views, Figure 1 is a plan of my improved condenser; Fig. 2 is an elevation thereof; Fig. 3 is a similar view taken at an angle of 90 degrees; Fig. 4 is a sectional view upon the line 4—4 of Fig. 1; Fig. 5 is an elevation of a casing containing a radio receiving set with a portion broken away to illustrate the mounting of the condensers upon the rear face of the panel; and Fig. 6 is a front elevation of such a casing containing a receiving set.

It will be understood that my invention is susceptible to various embodiments, and that the form thereof shown and described is merely illustrative. This embodiment of the invention however has been found to be practical in construction and operation, for which reason I have adopted it as my preferred form.

The invention may be said to comprise, first, the provision in a radio receiving set or receiving instrument of a panel face of insulating material upon the back of which is mounted elements forming the receiving set in such a manner as to avoid the use of special insulators; secondly, the production of a frame for a condenser element embodying portions of insulating material, whereby the necessity for insulated bushings and special provision for the insulating of the parts is avoided; and thirdly, the improvement of the details of construction of a rotary condenser whereby a minimum number of parts is required and a special ease of operation and compactness are accomplished.

These features will now be described in detail and their individual functions pointed out, after which a recital of the beneficial results due to their conjoint use will be given.

Referring to Figs. 5 and 6, the numeral 10 indicates a casing of wood supported by the feet or knobs 11, preferably of rubber, upon any suitable surface. The front or face 12 of the casing is made of a sheet of stiff insulating material, upon the back of which is mounted the several elements of a radio receiving set. I have preferred to illustrate my invention in connection with a panel of bakelite. This panel 12 is provided with

suitable openings through which project the spindles of the several control buttons or knobs 13, 14, 15, 16 and 17.

In Fig. 5 there is shown two condensers mounted upon the rear of panel 12, but it will be appreciated that a detailed description of the construction of one of them will suffice for both, and that a description of the method of mounting the condenser upon the back of the panel will suffice to set forth the general idea of mounting the elements of a radio set.

Referring to Figs. 1 to 4, the frame work of the rotary condenser comprises a pair of end plates 18 and 19 connected together by the bolts or posts 20 of which three have been deemed sufficient. Due to its insulating quality and to its ability to be made into smooth sheets as well as provided with screw-threaded apertures, I have preferred to make the plates 18 and 19 of bakelite, and have made them of the convenient shape illustrated in plan in Fig. 1, i. e., generally semicircular in form with a slightly angled base.

The plate 18 is provided with a pair of threaded apertures registering with a pair of unthreaded apertures in the panel 12, whereby a plate may be secured to the panel by means of machine screws 21 lying behind the control knob 13. It will be noted that the machine screws 21 are not in contact with any metal parts and therefore do not require further insulation.

The plate 18 is further provided with three threaded apertures located near its periphery in which I screw the bolts or posts 20 until they abut and are frictionally held against the rear face of the insulating panel 12. Upon the posts 20 I next place the stationary condenser plate 22 which lies flat against the insulating plate 18, and like the remaining stationary plates, has the general form of the plate 18 with the exception of its base which is provided with a recessed central portion, as shown by the dotted line 23 in Fig. 1. The ability to place this first condenser plate in contact with the end plate 18 produces a saving in space over the usual form of rotary condensers upon the market. Upon the posts 20 are next placed spacing sleeves 24, after which another condenser plate 25 is put into place. In like manner other spacing sleeves and condenser plates designated by the numerals 24¹ and 25¹ respectively are placed upon the posts 20, and finally the spacing sleeve 26, which as shown in Fig. 2 may be composed of two of the ordinary spacing sleeves.

The spindle 27 of the condenser is constructed with its central portion of relatively large diameter having at one end screw threads for the reception of a clamped nut 28 and at its opposite end a collar 29 which in the assembled condenser is designed

to have its outer face against the back of the plate 18. Beyond the threaded portion and the collar 29, the spindle is provided with reduced portions 30 and 31, respectively, which constitute the bearing portions 70 of the spindle, lying as they do in bearing apertures in the end plates 18 and 19. A shoulder 31 is formed by the reduced portion 30 and the end 31 is provided with a threaded bore, the purposes of both of which 75 features will hereinafter appear.

Before placing the spindle in the assemblage of the condenser, the rotating condenser plates 32 are placed thereon and spaced from each other by the sleeves 33 in 80 a manner analogous in all respects to that just described in connection with the stationary plates. The rotary plates have the form indicated in Fig. 1 by the numerals 34 and 34¹, 34 indicating the closed position of 85 the condenser plates and 34¹ the open position thereof. It will be appreciated that but a single opening is made in the rotary plates for this purpose and that the plates and sleeves are firmly clamped together 90 upon the spindle by the nut 28 whereby the aligned plates will be rotated with the spindle to place them in any desired position with respect to the stationary plates of the condenser. 95

After the stationary plates have been placed upon the posts 20 and the rotary plates upon the spindle, as described, the spindle end 31 is passed through the bearing aperture in plate 18,—this operation being permitted when the rotary plates are in the open position with respect to the stationary plates, as shown by the dotted line 34¹ in Fig. 1. The plate 19 is then placed upon the ends of the posts 20 and the end 30 of the spindle after which the nuts 35 are applied to the post ends and the plate 19 firmly held upon the posts in contact with the sleeves 26. 100

In this position of the parts it will be understood that the end 31 projects from the face of the panel 12 and upon this end is placed the control button or knob 13. For this purpose the knob is counterbored from either side to receive respectively the spindle end 31 and the head of the screw 36. The portion of the knob between said counterbores is provided with an aperture to receive the body of the screw. It will be appreciated that upon the tightening of the screw 36 the knob, which is preferably made of bakelite, will be firmly clamped to the spindle. In the rear face of the button or knob a recess is provided for the reception of the pointer 37 which cooperates with a dial upon the face of the panel 12 and indicates the relative position of the two sets of plates of the condenser as shown in Fig. 6. 110

It will be appreciated that the series of rotary condenser plates will be firmly held 115 120 125 130

in alignment with each other for movement with the spindle in its rotation. It is necessary in the use of a device of this type to have the spindle with the plates mounted thereon remain at any desired position. To accomplish this result I have provided a spring 38 which is attached to the underface of the plate 19 by the screw 39 and having its bifurcated end 40 bearing upon the shoulder 31 formed between the reduced end of the spindle and the screw threaded portion. The pressure of the spring produces the necessary frictional engagement of the collar 29 with the rear face of the end plate 18.

The spindle and the sleeves 33 establish the electric conductivity between the series of rotary plates, and the spring 38 is the means employed to conduct the current from the spindle 28. Any suitable electrical terminal may be provided for the projecting end of the screw 39 for the attachment of a lead wire. Electric conductivity is established between the several stationary plates by means of the posts 20 and the sleeves 24, and current may be conducted thereto through any suitable terminal attached to the end of one of the posts. I have shown for this purpose the sheet metal clip 41 to which the wire may be soldered.

From the foregoing description the operation of the condenser element will be apparent as well as the mode of assembling its parts, since these parts were described in the order of their emplacement. There remains to complete a full disclosure of invention only a recital of the conjoint use of the several details of construction.

The provision of an insulating panel and the mounting of an element of a radio set upon such panel by means of screws passing into an insulated portion of the element frame work avoids any danger of short-circuiting by reason of the mounting. It will be appreciated that the screws 21 do not touch any metal parts as their ends lie between the collar 29 and the edge of the recessed portion of the stationary plate 22, and their heads are protected by the knob 31. The provision of a frame work for the condenser composed of insulated front and rear plates obviates the necessity of providing special insulation for a metal frame element and permits the plate 22 to lie in contact with the frame parts. The apertures in the bakelite end members form efficient bearings for the spindle 27. The ends of the posts 20 are imbedded in the plate 18 and have their extremities abutting the panel 12; they are consequently fully protected and the arrangement acts as the equivalent of a nut lock for the posts. The spring 38 while producing the necessary friction for position holding also serves as an electrical conductor between the spindle

27 and the terminal 39. It will be appreciated that the details of construction produce an extremely compact condenser with a reduced number of parts and a special ability to be mounted in an efficient manner directly upon the rear face of the panel 12 with the full area of the plate 18 in contact with said panel.

What I claim is:

1. A variable condenser arranged to be mounted immediately adjacent an operating panel comprising in combination a set of stationary plates and a set of rotatable plates, a frame for mounting said stationary plates in spaced relation, said frame consisting of a pair of semi-circular end plates of flat insulating material angled on one edge thereof, a plurality of posts extending between said end plates with one of said stationary plates lying directly in contact with one of said end plates, and the others of said stationary plates equally spaced from each other upon said posts, and a shaft journaled directly in the angled portions of said insulated end plates and carrying said rotatable plates in position between said stationary plates, one of said flat end plates providing a surface for engagement with securing means extending through said operating panel.

2. A variable condenser arranged to be mounted immediately adjacent an operating panel comprising in combination a set of stationary plates and a set of rotatable plates, a frame for mounting said stationary plates in spaced relation, said frame consisting of a pair of semi-circular end plates of flat insulating material angled on one edge thereof, a plurality of posts extending between said end plates with one of said stationary plates lying directly in contact with one of said end plates, and the others of said stationary plates equally spaced from each other upon said posts, a rotary spindle journaled directly in the angled portions of said insulated end plates and comprising a collar at one end lying in contact with one end plate, a shoulder at the opposite end of said spindle formed by reducing the end thereof, a leaf spring attached to the second end plate and having a bifurcated end straddling said reduced spindle and producing frictional engagement between said collar and first end plate whereby said rotary spindle may be revolved to various positions and set with respect to said end plates when one of said end plates is secured directly adjacent said operating panel.

3. A variable condenser comprising in combination a framework consisting of front and rear plates of insulating material substantially semi-circular in contour bounded by an angled edge, connecting posts terminating in said insulated plates, stationary plates mounted on said connect-

ing posts and spaced one from another with one of said plates lying directly in contact with the inner face of said front plate throughout the area thereof, bearing apertures positioned directly adjacent the angled edges of said insulating plates, a rotating spindle mounted in said apertures

and carrying movable plates arranged to be rotated with said spindle in a horizontal plane with said front insulated plate forming the sole support for said condenser with reference to an adjacent surface. ¹⁰

OSBORNE I. PRICE.
